GARMENT HANGER

Elie Abraham Ghazal, Marion, S. C.

Application April 2, 1936, Serial No. 72,268

7 Claims. (Cl. 223—88)

This invention relates to improvements in garment hangers and is especially designed for supporting the neck and shoulder portions of the garment, and, in addition to provide means for retaining, or holding, the sleeve portions of the garment in such a position as to prevent wrinkling, or creasing, of the garment at the point where the sleeves are attached to the shoulder, or upper portions of the garment.

10 Garment hangers, so far as I am aware, do not have any means for positively retaining the sleeves fully extended, when on the hanger, for preventing creases therein. In my construction, the sleeve-extending means comprises two substantially elliptical-shaped bends of the wire in the parts that are inserted in the sleeves.

My garment hanger comprises a one-piece construction composed of wire, of suitable gage, so that it may be rigid when in use.

20 Broadly considered, it comprises two curved portions at the upper or neck portion of the hanger, the upper end portions of each of the curves having semi-circular loops that slide on each other, when in use. The lower ends of these 25 upper curves are connected to other and outwardly extending curves that are then formed into an elliptical-shaped loop for receiving the sleeves. One end of the loop is then coiled around the lower end of one of the outwardly 30 extending curves, at which point it extends across to the opposite end of the hanger and formed into a second elliptical-shaped curve, the end of which is then coiled around the other outwardly extending curved portion; it is then carried up and 35 coiled around the shank portion of the supporting hook.

Referring to the drawing:—

Fig. 1 is a perspective view, showing the complete garment hanger and clearly illustrating the 40 two elliptical-shaped sleeve-receiving portions.

Fig. 2 is a side, elevational view, showing the garment hanger in use, and

Fig. 3 is a detail view of one of the loops elliptical-shaped on the line 3—3 of Fig. 2.

45 Referring to the drawing in detail:—

1 designates the hook portion for supporting the garment hanger on any suitable member, as a rod. This hook portion is formed with the outwardly curved end 2. The shank part 3, of the 50 hook portion, is formed into a semi-circle 4, that extends downward in the upper curved portion 5 to the bend 6, where it is formed into the second outwardly extending curved portion 7 of a greater radius. The lower end 8 of the curved 55 portion 7 is formed into an elliptical-shaped

member 9 having a substantially long longitudinal axis, as indicated by the dotted line 10. The lower portion of the ellipse is bent slightly inward as indicated at 11 for strengthening purposes. The end 12 of the ellipse is then coiled around the lower end of the member 7, as indicated at 13. The wire then extends across the hanger, to provide the bar portion 14, which is coiled at 15 around the second elliptical-shaped member 16. The wire then extends upward at 10 17 to form the second outwardly extending curve 18 to the bent point 19 which corresponds to the bend 6. From this point, the wire is bent to form the second upper curve 20, which corresponds to the curve 5 and it is then looped to 15 form the second semi-circle 21; the free end of the wire is then twisted around the shank 3 of the hook, as indicated at 22.

It will be noticed that the two elliptical-shaped portions 9 and 16 do not hang exactly in a vertical plane, but extend slightly outward, as shown in Fig. 2, where they are inserted in the sleeves 23 of a garment. Fig. 2 shows the garment hanger, when in use with the two curved portions 5 and 20 supporting the collar portion of a garment and the two curved portions 7 and 18 supporting the shoulder portions of a garment. The elliptical members 9 and 16 are shown inserted in the sleeves for holding them outward, as illustrated by the dotted lines 24, whereby any wrinkles that would be formed at this part of the garment are fully prevented, by reason of the elongated loops which retain the sleeves extended substantially in the same position, as when the garment is being worn.

35 The two semi-circular portions 4 and 21 will slide slightly on each other, by reason of the overlapping and slideable contact at the point 25. In other words, this part of the hanger is slightly movable, so that the collar portion of the garment is kept smooth and free from wrinkles.

40 It will be seen, from this description, that I have provided a garment hanger that is formed of one piece of wire and is so constructed that it is rigid and one that will accurately position the 45 garment, when supported thereon, both as to the shoulder and neck portions, as well as the sleeve portions.

What I claim is:—

50 1. A garment hanger comprising, a one-piece member having a supporting hook portion, a plurality of curved portions of different radii connected to the hook portion, a bar member, the opposite ends of which are formed into sleeve-supporting loops that are connected to two of 55

the curved portions, and means for retaining the parts in their operative positions by spiral coils in the bar and hook portion.

2. A garment hanger as set forth in claim 1, having semi-circular loop portions that slide on each other at the shank portion of the supporting hook, whereby relative movements are obtained when in use.

3. A one-piece garment hanger comprising a supporting hook, two pairs of curved portions connected to the supporting hook with an intermediate overlapping and movable portion of the connected part, a cross bar, loops at the ends of the cross bar which are connected to one of the 15 pairs of curved portions.

4. In a garment hanger, a supporting hook, a cross bar formed into elliptical shaped sleeve-supporting loops at its opposite ends, and curved connecting means between the said loops and the 20 supporting hook, the planes of the loops being located away from a vertical plane, as described.

5. In a garment hanger, a supporting hook, separate curved portions connected to the hook for supporting the neck and shoulder portions of a garment respectively, a straight bar portion below said curved portions and in the same plane, and means for supporting the sleeves of a gar- 25

ment comprising closed loops connected to said curved portions and said bar portion for holding the sleeves suspended in spaced parallel planes, as described.

6. In a garment hanger, a supporting hook, 5 separate and connected curved portions connected to said hook for supporting the neck and shoulder portions of a garment respectively, a straight bar portion below said curved portions, said hook, curved portions, and bar portions being in the same plane, means for supporting the sleeves of a garment comprising closed elliptical-shaped loops connected to said curved portions and said bar portion, said loops being arranged 10 in planes which are angularly disposed relative 15 to the plane of the hook, curved portions, and bar portion.

7. In a garment hanger, a main frame comprising curved portions and a cross bar positioned in the same plane, loop elements integral 20 with said portions and said cross bar and located at the ends of said portions and said cross bar, said loops being positioned in planes perpendicular to the plane of said portions and said cross bar, and hook means integral with said 25 curved portions for suspending the hanger.

ELIE ABRAHAM GHAZAL.
